UNITED STATES PATENT OFFICE

ANDREW GRAHAM SHIELDS, OF ATTLEBORO, MASSACHUSETTS

COSMETIC CONTAINER

Application filed April 13, 1931. Serial No. 529,742.

My invention relates to devices adapted for the retention of a plurality of toilet preparations such as powder compacts and cosmetic pencils and refers particularly to devices of this character in which the withdrawal of the cosmetic pencil is facilitated.

In toilet preparation containers adapted to hold a cosmetic pencil in addition to other cosmetics it is desirable that the casing of the cosmetic pencil be capable of being contained within the container when the latter is in closed position and capable of presenting the pencil for easy removal from its carrier when the container is in open position.

Many containers have the pencil casing and pencil loosely positioned within them, thus requiring the removal of the casing from the container and necessitating the use of both hands in removing the pencil from the casing.

Attempts have been made to overcome the mentioned difficulty by pivotally connecting the pencil casing to the interior of the container, the casing and pencil resting within the container when it is in closed position. In order to remove the pencil from the casing in devices of this construction it is necessary to insert a finger into the casing compartment in order to pivotally move it to gain access to the pencil within it.

The device of my invention overcomes the mentioned objections to the aforescribed devices and presents a device in which the opening of the container will pivotally move the cosmetic pencil casing outwardly of the container presenting the pencil for immediate and ready removal from the casing.

The novelty and advantages of my device will be evident upon a consideration of my specification and accompanying drawings illustrating one form of the device of my invention.

In the accompanying drawings illustrating one form of my device similar parts are designated by similar numerals.

Figure 1 is a perspective view of one form of my device in closed position.

Figure 2 is a fragmentary top view of one corner of my device.

Figure 3 is a top plan view of the device of Figure 1 in open position.

Figure 4 is an enlarged section through the line 4—4 of Figure 3.

Figure 5 is an enlarged section through the line 5—5 of Figure 4.

Figure 6 is an enlarged fragmentary view of Figure 4.

The particular form of my device shown in the accompanying drawings consists of a casing having the top member 10 with the extended flanges 11, 12, 13 and 14 and the bottom member 15 having the extended flanges 16, 17, 18 and 19. The top side 11 and the bottom side 16 are hingedly attached to each other by the pintle 20 passing through ring members 21, 21 carried by the two sides, the top and bottom members thus forming a casing when closed upon each other.

Attached to the bottom 22 of the cosmetic pencil or cosmetic stick casing 23 is an extended member 24 having the expanded portion 25 and the end portion 26, the pintle 20 passing through an opening in the portion 25. Within the cosmetic-pencil casing 23, and longitudinally removable therefrom, is a cosmetic-pencil holder 28, within which is a cosmetic-pencil carrier 29 carrying the cosmetic-pencil 30.

The bottom member 15 has the wall 31 dividing it into two compartments, one of which 32 is adapted to receive a powder compact and the other of which 33 is adapted to receive the cosmetic-pencil casing 23.

A mirror 34 is hingedly attached between the top and bottom members by means of the pintle 20 and serves as a cover for the compartment 32.

A powder compact 35 and a powder puff 36 are positioned within the compartment 32.

The operation of the device is as follows:

When the device is closed, the cosmetic casing 23 and its contents are positioned within the compartment 33. As the top member and the bottom member are opened with respect to each other, the flange 11 of the top member 10 and the flange 16 of the bottom member 15 abut upon opposite sides of the element 26 thus causing the cosmetic-pencil casing to assume an upright position.

and allowing the withdrawal of the cosmetic-pencil holder 28, the cosmetic-pencil carrier 29 and the cosmetic-pencil 30.

It will thus be seen that in my device the opening of the container automatically erects the pencil casing and that the cosmetic-pencil can be readily withdrawn and replaced into position without releasing the container.

It will be further noticed that the operation of the cosmetic casing is a positive mechanical movement and is not dependent upon springs or other resilient means for its accomplishment.

I do not limit myself to the particular size, shape, number, arrangement or material of parts as shown and described as these are given simply as a means for clearly describing the device of my invention.

What I claim is:

1. In a container, in combination, a top member and a bottom member hingedly attached to each other, a pencil casing pivotally carried at the hinged jointure of said top member and said bottom member and capable of normal placement within the closed container, a member carried by said pencil casing extending outwardly of the container at the said hinged portion adapted to raise said pencil casing from its normal position within the closed container when said top member and said bottom member are hingedly moved with respect to each other causing an opening of said container.

2. In a container, in combination, a top member and a bottom member hingedly attached to each other, a pencil casing pivotally carried at the hinged jointure of said top member and said bottom member and capable of normal placement within the closed container, a member carried by said pencil casing extending outwardly of the container at the said hinged portion and so positioned that a movement of said top and bottom members will cause said top and bottom members to abut thereon causing said pencil casing to be raised to an erect position from said casing.

3. In a container, in combination, a top member and a bottom member hingedly attached to each other, a pencil casing pivotally carried at the hinged jointure of said top member and said bottom member and capable of normal placement within the closed container, a member carried by said pencil casing extending outwardly of the container at the said hinged portion so positioned that a movement of said top and bottom members will cause said top and bottom members to abut thereon causing said pencil casing to be raised to an erect position from said casing during the opening movement of said container and maintaining said pencil casing in said erect position.

4. In a container, in combination, a top member having flange sides, a bottom member

having flange sides, hinge means connecting the top member and the bottom member, a pencil casing hingedly carried by said hinge means and capable of normal placement within said container when said container is closed, and an element carried by said pencil casing extending outwardly of said container and capable of abutment upon a top member flange and a bottom member flange when said container is open, said abutment causing said pencil casing to assume an erect position during the opening movement of said container.

5. In a container, in combination, a top member and a bottom member hingedly attached to each other, a pencil casing pivotally carried at the hinged jointure of said top member and said bottom member and capable of normal placement within the closed container, and means exterior of said container carried by said pencil casing causing said pencil casing to assume an erect position when said top member and said bottom member are hingedly removed with respect to each other causing an opening of said container.

6. In a container, in combination, a top member and a bottom member hingedly attached to each other, a pencil casing pivotally carried at the hinged jointure of said top member and said bottom member and capable of normal placement within the closed container, means exterior of said container carried by said pencil casing causing said pencil casing to assume an erect position when said container is being opened and maintaining said pencil casing in said erect position.

7. In a container, in combination, a top member having flange sides, a bottom member having flange sides, hinge means connecting the top member and the bottom member, a pencil casing hingedly carried by said hinge means and capable of normal placement within said container when said container is closed, an element carried by said pencil casing extending outwardly of said container and capable of abutment upon a top member flange and a bottom member flange when said container is open, said abutment causing said pencil casing to assume an erect position during the opening movement of said container and maintaining said pencil casing in said erect position.

Signed at New York in the county of New York and State of New York this 9th day of April, 1931.

ANDREW GRAHAM SHIELDS.
